ATT'Y

UNITED STATES PATENT OFFICE.

MINNIE T. DURGY, OF SHERMAN, CONNECTICUT.

SKILLET.

SPECIFICATION forming part of Letters Patent No. 429,169, dated June 3, 1890.

Application filed October 23, 1889. Serial No. 327,916. (No model.)

To all whom it may concern:

Be it known that I, MINNIE T. DURGY, a citizen of the United States, residing at Sherman, in the county of Fairfield and State of Connecticut, have invented certain new and useful Improvements in Skillets; and I do hereby declare the following to be a full, clear, and exact description of the invention, such as will enable others skilled in the art to which it appertains to make and use the same.

My invention relates to certain new and useful improvements in the construction of devices designed to be attached to skillets to prevent the cooking fats, &c., from bespattering the stove or neighboring objects.

It is the aim of my invention to afford by my improvement all the advantages of a closed cover, and to do away with the necessity of removing the latter whenever it becomes necessary to inspect or manipulate that which is in the skillet.

Another, and in fact the chief, object of my invention is to provide for the ready insertion and manipulation of culinary tools within the skillet.

In the accompanying drawings, Figure 1 shows a sectional elevation of my improvement applied within an ordinary skillet; Fig. 2, a detail perspective of my improvement; Fig. 3, a view similar to Fig. 1, but showing in addition hooks extending from my improvement over the edge of the skillet; and Fig. 4, a detail elevation of my improvement provided with such hooks.

Similar letters denote like parts in the several figures of the drawings.

A is the skillet, of ordinary construction.

B is what I term my "improved skillet-extension," which is open at the top and bottom. The bottom C of this extension is shaped to such an angle that it will closely

fit the inner wall of the skillet, while the height of the extension above the skillet is such that the particles of grease, &c., will not be likely to spatter outside of said extension. 45

The nose of my extension is flared, as seen at D, so as to afford an easy incline, whereby the culinary tools may be readily handled when inserted within the skillet. Lips may be cut from the stock of the bottom C and bent 50 into the form of hooks E, which are adapted to fit snugly over the edge of the skillet in order to still further secure the extension within the skillet.

I do not wish to be understood as basing 55 any novelty on a skillet-extension open at the top and bottom, for this I know to be old; but the adaptation of the bottom of the extension to fit closely within the skillet and the provision of a flared nose are features 60 which I believe to be new and patentable.

The extension may be turned around within the skillet to any desired position, and the flared nose also affords a handle whereby said extension may be readily applied within or 65 removed from the skillet.

Having thus fully described my invention, what I claim as new, and desire to secure by Letters Patent, is—

1. A skillet-extension open at the top and 70 bottom and having a flared nose, substantially as shown and described.

2. A skillet-extension having its bottom open and shaped to snugly fit within the skillet, and provided with an open top having a 75 flared nose, substantially as set forth.

In testimony whereof I affix my signature in presence of two witnesses.

MINNIE T. DURGY.
